CLAIM

The ornamental design for an intra-vascular catheter assembly, as shown and described.

DESCRIPTION

FIG. 1 is a perspective view of an intra-vascular catheter assembly showing our new design;

FIG. 2 is a front elevational view thereof;

FIG. 3 is a rear elevational view thereof;

FIG. 4 is a top plan view thereof, the bottom plan view being a mirror image;

FIG. 5 is a left side elevational view thereof;

FIG. 6 is a right side elevational view thereof;

FIG. 7 is a cross-sectional view thereof taken along the line VII—VII in FIG. 2; and,

FIG. 8 is a cross-sectional view thereof taken along the line VIII—VIII in FIG. 2.

FIG. 1
